ABSTRACT OF THE DISCLOSURE

Polynuclear aromatic hydrocarbons such as coal extract are hydrocracked in the presence of molten zinc halide and zinc oxide.

This invention relates to the catalytic hydrocracking of predominantly polynuclear aromatic hydrocarbonaceous materials, and particularly to the conversion to gasoline of substantially nondistillable high molecular weight predominantly polynuclear aromatic hydrocarbonaceous feedstocks which may contain appreciable quantities of nitrogen, oxygen and sulfur compounds, as well as unfilterable ash contaminants.

U.S. patent application Ser. No. 449,904, filed Apr. 21, 1965, describes such a process and utilizes as a catalyst molten zinc halides. This patent application sets forth that polynuclear hydrocarbons including but not limited to those which are nondistillable, may be readily converted to a low boiling liquid suitable as a fuel such as gasoline in the presence of a large quantity of molten zinc halide.

An object of this invention is to provide a process for hydrocracking polynuclear aromatic materials by contacting a feedstock which is heavier than gasoline with hydrogen and a zinc halide salt at elevated temperatures. Another object of this invention is to provide this process with a zinc oxide acceptor for removing hydrogen chloride from the system. In particular it is an object of this invention to convert polynuclear aromatic hydrocarbonaceous material to gasoline in the presence of a catalytic-acceptor composition comprising zinc halide salt and zinc oxide in a mole ratio of at least ten parts halide to one part oxide.

These and other objects and features of the invention will be seen in the following description and in the appended drawing, in which:

FIG. 1 is a schematic representation of the basic process;

FIG. 2 shows the hydrocracking portion of the system; and

FIGS. 3 and 4 show alternate embodiments of the regeneration steps for receiving spent catalyst.

The present invention is an improvement in the hydrocracking process described in the above-mentioned application. Accordingly, in order to understand the present invention, it is necessary to review the essential elements of the basic process. FIGURE 1 shows these schematically. For convenience in reference, zinc chloride, $ZnCl_2$, is used as illustrative of the catalyst, and coal extract as illustrative of a sulfur- and nitrogen-containing polynuclear hydrocarbon. Numeral 10 designates a suitable Hydrocracking Zone to which coal extract and hydrogen are fed through conduits 12 and 14, respectively. Regenerated molten zinc chloride is introduced through conduit 16 into the Hydrocracking Zone 10 from a Regeneration Zone 18. The operating conditions maintained in the Hydrocracking Zone 10 are as follows:

Temperature ----- 500-875° F.
Pressure ----- 500-10,000 p.s.i.g.
Liquid hourly space velocity ----- 0.25-4.20.
H₂ feedstock ratio ----- 5-50 s.c.f./lb.

5 $ZnCl_2$ catalyst ----- At least 15 wt. percent of hydrocarbon inventory in the Hydrocracking Zone.

The hydrocracked products, i.e., low boiling hydrocarbons, are withdrawn through a conduit 20. Spent catalyst is conducted to the Regeneration Zone 18 via a conduit 22.

Normally, the reactions occurring in the Hydrocracking Zone are as follows:

In accordance with the present invention, we have found that zinc oxide is extremely useful in the Hydrocracking Zone as an acceptor, as set forth in the following equation:

By virtue of the use of zinc oxide, loss of HCl from the system is minimized, and corrosion by HCl is controlled. The use of zinc oxide also effectively eliminates the reaction expressed in Equation 3 above, thus making it unnecessary to regenerate $ZnCl_2$ from $ZnCl_2 \cdot NH_4Cl$.

The amount of zinc oxide in the Hydrocracking Zone must be carefully regulated, since the catalytic effectiveness of the latter is seriously inhibited by excessive amounts. We have found that the zinc oxide concentration must be kept lower than a $ZnO/ZnCl_2$ mol ratio of 0.10, and preferably below 0.05. Table I below shows the effect of different molar ratio of ZnO to $ZnCl_2$ on the conversion of nondistillable coal extract to distillate, and also on the yield of low boiling gasoline stock, i.e., the $C_5 \times 200^\circ C.$ portion of the distillate product.

TABLE I

Run No.	26	23	36	68	67
Temperature, ° C.	427	427	427	399	399
Total Hot Pressure, P.s.i.g.	4,200	4,200	4,200	3,000	3,000
Residence Time, Min.	60	60	60	60	60
Feed Gm.:					
Extract	50.0	50.0	50.0	50.0	50.0
$ZnCl_2$	50.0	50.0	50.0	50.0	100.0
ZnO	0	25.0	2.50	2.50	2.50
$ZnCl_2/Extract$, Wt. Ratio	1.0	1.0	1.0	1.0	2.0
$ZnO/ZnCl_2$, Mol Ratio	0	0.84	0.084	0.084	0.042
Yields, Wt. Percent MAF Feed:					
(C_1-C_3)	13.0	4.6	10.2	3.4	5.9
$i-C_4H_{10}$	9.6	1.5	6.3	1.4	5.9
$n-C_4H_{10}$	1.6	0.5	1.1	0.2	0.9
$C_5 \times 200^\circ C.$ Distillate	60.4	25.5	42.5	39.4	61.0
$200 \times 400^\circ C.$ Distillate	3.1	23.5	23.4	21.0	4.5
Hydrogen Consumed, Wt. Percent MAF Feed	8.7	5.0	7.6	5.6	7.4
Conversion, Wt. Percent MAF Feed	89.8	58.8	84.2	69.0	79.8

The following conclusions are evident from the data in the above Table I:

80 (1) High concentrations of ZnO severely inhibit the hydrocracking activity of $ZnCl_2$, not only with regard to total conversion, but also with regard to cracking to gasoline (see Run No. 23).

(2) A $ZnO/ZnCl_2$ mol ratio lower than 0.10, e.g., 0.084, is required to get a high conversion to distillate (see Run No. 36); and a $ZnO/ZnCl_2$ mol ratio lower than 0.05, e.g., 0.042 is required to get a high yield of gasoline (i.e. $C_5 \times 200^\circ C.$ distillate) (see Run No. 67).

65 FIGURE 2 shows schematically a hydrocracking system in which the molten zinc chloride catalyst is introduced as two separate streams, one as $ZnCl_2$, without any zinc oxide, and the other as zinc oxide-rich $ZnCl_2$. The

oxide-rich $ZnCl_2$ is added to the latter stages of the hydrocracking system to remove the HCl.

The hydrocracking system comprises a plurality of hydrocracking vessels 30, each of which contains two Hydrocracking Zones 32 and 34, one above the other, so that the effluent gases and vapors from zone 34 pass through zone 32 into a common outlet conduit 36. The Hydrocracking Zones are connected together for sequential flow of unconverted feedstock by connecting pipes 38. Each zone downstream is maintained at a somewhat higher temperature than the preceding zone so that there is a temperature gradient between the first and the last of the zones. Hydrogen gas is furnished to the Hydrocracking Zones via a main inlet conduit 37 and a manifold 39 leading to the bottom of each of the vessels 30. The temperature, pressure, and other conditions are the same as those recited in the description of the Hydrocracking Zone of FIGURE 1.

Coal extract and molten zinc chloride, free of oxide, are introduced through conduits 40 and 42, respectively, into a conduit 44 leading to the first of the Hydrocracking Zones 32. The nondistillable coal extract is partially converted to vaporous distillate which is withdrawn through the outlet conduit 36. The unconverted portion of the coal extract is transferred by conduit 38 to the next Hydrocracking Zone 32, and so on until the last zone 32 has been reached, and thence on sequentially through the lower Hydrocracking Zones 34. At the last zone 34, the liquid mixture comprises mostly spent catalyst, organic residue and even carbon. This mixture is sent to a Regeneration Zone through a discharge pipe 46.

The effluent gases and vapors withdrawn through the common conduit 36 are passed through a slurry of molten zinc chloride and zinc oxide contained in a vessel 48. This vessel is continuously supplied with the slurry via a conduit 50. The zinc oxide in the slurry absorbs HCl contained in the effluent gases. HCl-free gas is recovered through a conduit 52. The slurry of zinc chloride and zinc oxide is conducted through a main conduit 54 to two separate manifold lines 56 and 58, respectively, which supply zinc oxide and supplemental fresh zinc chloride catalyst to each of the Hydrocracking Zones. The zinc oxide serves as an acceptor for most of the HCl generated, the residual HCl being absorbed as mentioned in the cleanup absorption vessel 48.

FIGURE 3 shows a simple version of a regeneration scheme based on oxidation at elevated temperatures of sulfur, carbon and nitrogen components in a liquid phase process. The reactions occurring in such a regeneration process are as follows:

Spent catalyst containing $ZnCl_2^2$, $ZnCl_2 \cdot NH_3$, ZnS , and carbon is introduced through a conduit 60 into the intermediate section of a combustion tower 62. Air is pumped into the bottom of the tower through a conduit 64. The temperature and pressure are regulated to maintain the oxidative reactions set forth above. The regenerated liquid is withdrawn through a conduit 66 and passed through a heat exchanger 68 to cool down the zinc chloride. The latter is then conveyed via conduit 70 either to a recycle conduit 72 or to a conduit 74 for returning the regenerated catalyst to the Hydrocracking Zone. The products of oxidation, i.e., flue gas, are discharged via a conduit 76 from the combustion tower 62.

FIGURE 4 shows another process for regenerating spent catalyst from the Hydrocracking Zone. According to this process, the entire spent catalyst is incinerated at high temperatures by combustion of the carbon and sulfur components of the molten catalyst, and any residual

ammonia that may have remained in the melt as well. This process is applicable to those cases where the coke yield is relatively high, of the order of 3 percent or more by weight of the coal extract. Under these conditions, the heat of combustion of the spent catalyst is sufficient to vaporize all of the zinc chloride present in the spent melt. Thus, it is possible to inject the melt into a fluid bed of carbon and volatilize all of the zinc chloride while burning carbon and sulfur in solid form.

Referring to FIGURE 4, spent catalyst from the Hydrocracking Zone is introduced via a conduit 80 into a combustion zone 82. The carbon, sulfur, and any nitrogen components in the spent catalyst are oxidized by air fed to the combustion zone via conduit 84. The heat developed in this zone is sufficient to vaporize all the zinc chloride. The latter in vapor form, together with entrained zinc oxide, is withdrawn through a conduit 86 to a combined condenser and scrubber 88. A portion of the zinc chloride is condensed. The condensate and zinc oxide form a slurry which is discharged through a conduit to a heat exchanger 92 for cooling to a temperature between about 1000 and 1100° F. The cooled ZnO slurry in $ZnCl_2$ is returned to the Hydrocracking Zone through conduits 94 and 96. A portion, however, is recycled via a conduit 98 to the condenser-scrubber 88 to condense the solids-laden vapors from the combustion vessel 82.

$ZnCl_2$ vapors and noncondensable gases, i.e., CO , CO_2 , N_2 , and HCl are withdrawn from the condenser 88 through a conduit 100 to another condenser 102 wherein the remaining traces of $ZnCl_2$ are condensed. The pure $ZnCl_2$ melt is discharged through a conduit to a cooler 106, and thence through a conduit 108 back to the Hydrocracking Zone. A portion of the cooled melt is recirculated to the condenser 102 via a conduit 110.

Noncondensable gas, including HCl , is withdrawn from the condenser 102 through a conduit 112. A slip-stream of ZnO in $ZnCl_2$ slurry from conduit 98 is introduced into conduit 112, to provide ZnO to neutralize any HCl , thus forming some $ZnCl_2$. Any $ZnCl_2$ so formed is cooled in a heat exchanger 114 and carried via conduit 116 to a condenser 118 where the $ZnCl_2$ is condensed. The noncondensable gases are discharged via conduit 120. The $ZnCl_2$ melt at this point may contain some ash or contaminant solids. Accordingly, the melt is withdrawn via a conduit 122 to a filter 124 where the ash is separated and discharged through a conduit 126. The $ZnCl_2$ melt is transported via conduits 128 and 96 back to the Hydrocracking Zone. ZnO may be added as make-up via conduit 130 to control the ZnO concentration in the $ZnCl_2$ slurry.

What is claimed is:

- 50 1. In the process for converting polynuclear aromatic hydrocarbonaceous feedstock to gasoline by hydrocracking wherein the feedstock is contacted with molten zinc chloride in the presence of hydrogen at elevated temperature and pressure to effect hydrocracking of the feedstock,
- 55 the improvement which comprises maintaining a mixture of zinc chloride and zinc oxide in a hydrocracking zone, said chloride and oxide being in a mole ratio of at least ten parts chloride to one part oxide.
- 60 2. The process of claim 1 wherein the feedstock contains appreciable quantities of nitrogen and sulfur compounds.
- 65 3. The process of claim 2 in which the feedstock is coal extract.
- 70 4. The process of claim 1 wherein spent zinc chloride and zinc oxide is regenerated and returned to the hydrocracking zone.
- 75 5. The process of claim 1 wherein effluent gas from the hydrocracking zone is contacted in a contacting zone with a mixture of zinc chloride and zinc oxide to remove hydrogen chloride gas from the effluent gas.
- 80 6. The process of claim 5 wherein effluent from said contacting zone is conveyed to said hydrocracking zone, said effluent comprising zinc chloride and zinc oxide.
- 85 7. A process for converting polynuclear aromatic hydrocarbonaceous feedstock to gasoline comprising serial-

ly passing said feedstock through a plurality of hydro-cracking zones, each zone containing molten zinc chloride, at least one hydrocracking zone downstream from the first zone in said series of zones containing zinc oxide in admixture with said molten zinc chloride, said chloride and oxide being in a mole ratio of at least ten parts chloride to one part oxide; and passing effluent gases from downstream zones in said series of zones through upstream zones in said series of zones.

8. The process of claim 7 further comprising contacting effluent gases from said upstream zones with a slurry of molten zinc chloride and zinc oxide.

9. The process of claim 8 further comprising passing effluent slurry from said slurry-effluent gases contacting step to at least one hydrocracking zone downstream from said first zone in said series of zones.
